UNITED STATES PATENT OFFICE.

CHARLES M. HEETER, OF BUTLER, PENNSYLVANIA.

CASING-HEAD ATTACHMENT.

1,366,075.

Specification of Letters Patent. Patented Jan. 18, 1921.

Application filed September 14, 1916. Serial No. 120,185.

To all whom it may concern:

Be it known that I, CHARLES M. HEETER, a citizen of the United States, and resident of Butler, in the county of Butler and State 5 of Pennsylvania, have invented certain new and useful Improvements in Casing-Head Attachments, of which the following is a specification.

The object of this invention is to provide 10 improved sealing means for the casing head of an oil well by means of which a string of tubing may be either entered or withdrawn without oil or gas escaping from the casing. The improved device is readily applied to 15 casing heads of usual construction, and is intended for use only when entering or withdrawing the tubing, at other times the casing head being closed by the usual casing head cap or closure well known in the art. 20. In the accompanying drawings, Figure 1 is a view in top plan of the improved attachment. Fig. 2 is a sectional elevation of the same in position on the casing head.

Referring to the drawings, 2 designates a 25 casing head of usual construction which is formed with a through vertical passage to the lower end of which the well casing 3 connects. The casing head is provided with the usual lateral gas or oil outlets 4, and 30 at its upper end is formed with the depressed seat 5. This seat is adapted to receive a cap or closure (not shown) of ordinary construction, also the attachment comprising the present invention, such closure or attachment, as the case may be, being secured by the set screws 6 entering through the upstanding flange 5' of seat 5.

The improved attachment consists of the 40 upper and lower head-like sections 7 and 8, respectively, which are adapted to be secured together by the clamping bolts 9, section 7 formed with base flange 7' which rests on seat 5 on which it is secured by screws 6. The under side of section 8 is recessed upwardly at 10 to receive the diaphragm 11 of rubber or other flexible material. Projecting from the opposed clamping faces of the heads 7 and 8 are the annular V-shaped flanges or ridges 12, which 45 when the heads are clamped together are impressed in the opposite faces of the diaphragm to insure a sealed joint.

The through passageway in heads 7 and 8 for tubing 13 is flared or enlarged at opposite sides of the diaphragm so that the latter may flex as the tubing is passed through the center opening therein, the de-

flection being downward as the tubing is passed into the casing and upward as it is removed therefrom. The opening through 60 the diaphragm is of such size that the latter is caused to closely fit around the tubing, preventing the escape of any gas or oil under pressure within the casing. The flexibility or elasticity of the diaphragm is 65 such that the tubing couplings 13' may be passed either upwardly or downwardly therethrough without breaking the seal. After the tubing has been placed in position in the casing or after it has been withdrawn therefrom, the improved attachment 70 is replaced by a casing head cap or closure of usual construction.

The advantage of the invention results 75 from the effective sealing of the casing during the operations of lowering and withdrawing the tubing without in any way interfering with those operations.

I claim:

1. A casing head attachment, comprising 80 two superimposed sections having interiorly enlarged registering vertical openings therethrough, the lower section having a base adapted to engage the usual cap or closure seat of a well casing, a packing diaphragm 85 seated and clamped between the opposing faces of said sections, one of said sections having a vertical spacing flange surrounding the edge of the diaphragm and adapted to contact with the other section to limit the 90 approach of said sections, and clamping means for securing said sections together, substantially as described.

2. A casing head attachment, comprising 95 two superimposed sections having interiorly enlarged registering vertical openings therethrough, the lower section having a base adapted to engage the usual cap or closure seat of a well casing, a packing diaphragm seated and clamped between the 100 opposing faces of said sections, one of said sections having a vertical spacing flange surrounding the edge of the diaphragm and adapted to contact with the other section, a centering means on the other of said sections 105 for coöoperating with said spacing flange, and clamping means for securing said sections together, substantially as described.

In testimony whereof I affix my signature in the presence of two witnesses.

CHARLES M. HEETER.
